UNITED STATES PATENT OFFICE.

EDWARD J. HARTMAN, OF CINCINNATI, OHIO.

MOP WRINGER.

Application filed May 27, 1920, Serial No. 384,772. Renewed March 18, 1926.

To all whom it may concern:

Be it known that I, EDWARD J. HARTMAN, a citizen of the United States of America, and resident of Cincinnati, in the county of 5 Hamilton and State of Ohio, have invented a new and useful Improvement in a Mop Wringer, of which the following is a specification.

An object of my invention is to provide a 10 mop wringing device that may be readily attached to or detached from an ordinary bucket.

Another object is to provide a device for 15 the purpose stated that can be used in connection with a bucket without being attached thereto, and that after use can be easily cleaned and aired.

Another object is to provide a device that 20 can be so adjusted so that the mop may be wrung to various degrees of moisture.

These and other objects are attained by means described herein and disclosed in the accompanying drawing in which:

Fig. 1 is a perspective view of a device 25 embodying my invention, and mounted upon a bucket.

Fig. 2 is a fragmental sectional view looking toward the right on Fig. 1.

Fig. 3 is an enlarged sectional view on 30 line 3—3 of Fig. 2.

My invention comprises the frame A having the slotted sides a and a' and the end a^2 upon which is mounted the notched lug a^3 . The fixed roller a^4 is secured between 35 the sides a and a' . The movable roller a^5 is supported between the sides a and a' of the frame and the arms a^6 and a^7 of the yoke a^8 by means of the axial bearing a^9 which passes thru the slots in the sides a and a' and the arms of the yoke. The links a^{10} and a^{11} are pivotally attached to the frame 40 A and to the arms a^6 and a^7 of the yoke.

The rod B is attached to the yoke by the 45 pivot b . The hollow sleeve b' upon the upper end of which is a handle b^2 , partly encloses the rod B. A shoulder b^3 formed on the lower end of the sleeve forms a seat for spring b^4 mounted upon the rod B. The upper end of the rod B is screw threaded 50 and upon such threaded section is mounted the nut b^5 . The nut b^5 holds the spring inside of the sleeve, and by adjusting the screw the pressure upon the spring is varied.

The legs or U shaped metallic frames C 55 are adapted to engage the frame A and to prevent the frame being moved upward

when the mop is drawn upwardly between the rollers.

The bucket D may be of any type or kind.

The operation of my device is as follows: 60

The frame A is placed over a bucket in the position shown in Fig. 1. The sleeve b' and the rod B are disengaged from the lug a^3 thereby permitting the roller a^5 to be moved to the end of the slots adjacent 65 to the links a^{10} and a^{11} . The operator then inserts the mop in the bucket between the roller a^4 and a^5 . When the operator desires to wring the mop, the roller a^5 is moved toward the roller a^4 by pulling upward upon 70 the handle b^2 until the rod B can enter the notch in the lug a^3 . The handle is released and the sleeve b' engages the lug a^3 . The operator stands upon the feet c and c' formed on the legs C and then pulls the mop 75 upward between the rollers a^4 and a^5 . The degree of the moisture retained by the mop may be varied by reducing the operating space of spring b^4 by means of nut b^5 upon rod B. The guards E prevent the mop clog- 80 ging the rollers.

The guards E are mounted on the frame between the rollers and extending over the outer edges of the rollers and are adapted to prevent the mop engaging the bearings 85 upon which the rollers are mounted and thereby avoiding jamming of the rollers and clogging of the device.

What I claim is:

1. In a mop wringer the combination of 90 a frame, a fixed roller in the frame, a roller mounted reciprocally within the frame, arms pivotally connected to the movable roller and the frame, a handle secured to the arms and means for locking the handle in the 95 frame.

2. In a mop wringing device, the combination with a frame, having slotted sides, a fixed roller mounted between the slotted sides, a yoke, links, pivots connecting the 100 links to the frame and to the yoke, a movable roller, an axial bearing extending thru the movable roller, thru the arms of the yoke, and thru the slots in the frame, means to reciprocate the bearing in the slots and means to lock the rollers in fixed relation to one another.

3. In a mop wringing device the combination with a frame, a notched lug upon the end of the frame, a fixed roller and a 110 movable roller supported between the sides of the frame, a rod connected with the mov-

able roller, an adjustable nut upon the rod, a hollow sleeve mounted upon the rod, a spring mounted upon the rod interiorly to the sleeve and adapted to engage the sleeve 5 at its lower end and the nut at its upper end, and a handle upon the sleeve, the sleeve being adapted to compress the spring upon the nut and to engage the notched lug while the rod is seated in the notch therein whereby a 10 mop may be held between the rollers.

4. In a mop wringing device the combination with a frame, a notched lug upon the end of the frame, a fixed roller and a movable roller supported between the sides of 15 the frame, a rod connected with the movable roller, an adjustable nut upon the rod, a hollow sleeve mounted upon the rod, a spring mounted upon the rod and within the sleeve and adapted to engage the sleeve at its lower end and the nut at its upper end, a handle upon the sleeve, the sleeve being adapted to compress the spring upon the nut and to engage the notched lug while the rod is seated in the notch therein, whereby 20 a 25 mop may be held between the rollers, and

means secured to the frame upon which an operator may stand to removably support the device over a bucket against the upward movement of the mop between the rollers.

5. In a mop wringer, the combination 30 of a substantially horizontal roller frame adapted to removably rest upon the top of a bucket, rollers mounted in the frame for wringing mop heads, and anchor frames 35 each comprising a rod bent into substantially U-shape, the free end of each arm of said rod being formed into a hooked end, the hooked ends being capable of insertion in apertures in the roller frame, the anchor frames being bent outwardly adjacent the bent portion and the places spaced from the hooks, whereby to form feet at the bases of the anchor frames serving as means upon which an operator may stand to preclude upward movement of the roller frame when 40 a mop head is drawn between the rollers. 45

In witness whereof, I have hereunto subscribed my name this 19th day of May, 1920.

EDWARD J. HARTMAN.
